METHOD OF AND MEANS FOR SCREEN VENTING A CORE BOX

Otto P. Yahnka, Dearborn, Mich.

Application February 6, 1958, Serial No. 713,726

8 Claims. (Cl. 22—13)

This invention relates generally to shell molding, and, more particularly, to a novel and improved method of and means for venting a corebox for shell molding.

In the past, when making sand cores for casting purposes the core was made in a corebox, that is, formed to the desired shape in the corebox, and then it was taken out and baked. The aforementioned method of making cores has been replaced in the past few years by a method of core making called in the art shell molding. In the latter mentioned method the shell core is baked in the corebox. The sand mixture employed in making shell cores is delivered to the corebox by means of forced air. At present, the coreboxes used in shell molding are provided with vents employing wire mesh screens which clog up in a short time, that is, in a matter of a day or less. The screen then must be taken out and cleaned and this results in much down time with a further resultant loss of production output and money. Furthermore, during the baking process the sand mixture is baked onto the screens and the corebox cannot be properly vented. Such action results in the sand not being packed firmly in the corebox and a spongy core is produced. Then when such a spongy core is used in a casting operation the resultant casting will have fuzzy protrusions around the surfaces thereof and such castings have to be scrapped.

It is an important object of this invention to provide a method of and means for screen venting a corebox during a shell molding operation whereby the corebox may be efficiently and properly vented so as to permit the sand mixture to be completely packed to produce a solid or homogeneous core.

It is another object of this invention to provide a novel vent for a corebox which is simple and rugged in construction, economical of manufacture, and efficient in operation.

It is a further object of this invention to provide a novel vent for a corebox adapted for use in a shell molding operation which is self-cleaning and which may be mounted to vent any desired shape or angle formed by the inner surface of the corebox which determines the shape of the core to be produced.

Other objects, features and advantages of this invention will be apparent from the following detailed description and appended claims, reference being had to the accompanying drawings forming a part of the specification wherein like reference numerals designate corresponding parts of the several views.

In the drawings:

Fig. 1 is an elevational sectional view of a shell molding corebox provided with vents made in accordance with the principles of the invention;

Fig. 2 is a side elevational view of a vent embodying the invention;

Fig. 3 is an end view of the structure illustrated in Fig. 2, taken along the line 3—3 thereof, and looking in the direction of the arrows;

Fig. 4 is an elevational central sectional view of the

2

structure illustrated in Fig. 2, taken along the line 4—4 thereof;

Fig. 5 is a fragmentary elevational sectional view of a corebox having a shaped inner surface and provided with a vent made in accordance with the invention;

Fig. 6 is a broken, fragmentary elevational sectional view of a corebox provided with a vent means in accordance with the invention;

Fig. 7 is a fragmentary elevational sectional view of a prior art type corebox screen vent; and

Fig. 8 is an end view of the screen vent illustrated in Fig. 7, taken along the line 8—8 thereof, and looking in the direction of the arrows.

Referring now to the drawings, and in particular to Figs. 1 through 4, the numeral 10 generally designates a corebox of the type used in shell molding. The corebox 10 includes the usual bottom, top, and side walls 11, 12, 13 and 14, respectively. The corebox 10 also includes end walls as 15 at each end thereof. The corebox 10 is provided with the usual inlet conduits as 16 through which is delivered by means of forced air the sand mixture for making the core. The corebox 10 may be provided with a shaped lining or wall section as 17 along the inner faces of the corebox walls. When used in the claims in this application, the term corebox wall is taken to include this lining or wall section 17.

The numeral 18 generally designates a corebox vent made in accordance with the principles of the invention. A corebox provided with the vent 18 would have a plurality of these vents disposed in the walls thereof and at the positions most optimum for venting. The vents 18 are mounted in the walls of the corebox as shown in Fig. 1. For each vent 18 a hole as 19 would be bored in the corebox wall to a diameter slightly less than the diameter of the circular vent 18. That is, the diameter of the vent 18 overall would be approximately .002" larger than the hole 19. The vent 18 is then press fitted into the hole 19.

The vent 18 includes the cylindrical body 20 having the inner end 21 which is adapted to be disposed level or even with the inner surface of the wall of the corebox in which it is disposed. The body 20 is provided with an axial aperture therethrough which tapers outwardly or diverges outwardly from the inner end 21 of the body 20 to the outer end 24 thereof. The diverging hole through the body 20 diverges from the circular opening 22 at the inner end of the body 20 to the larger circular opening 23 at the outer end of the body 20. A preferred angle of divergence for this hole is 5° as indicated in Fig. 4.

Centrally mounted, or axially disposed, within the hole 20 through the body 20 is a truncated pin generally indicated by the numeral 25. The inner end 26 of pin 25 is adapted to be even or level with the inner end 21 of the body 20. The inner end 26 of the pin 25 is disposed concentrically with the inner end 22 of the hole through the body 20. The outer surface 27 of the pin 25 converges outwardly, or tapers outwardly of the corebox but inwardly towards the axis of the pin 25. A preferred angle of convergence for the pin 25 is 5° as indicated in Fig. 4. The inner end 26 of the pin 25 is preferably disposed in the hole in the body 20 with a peripheral clearance therebetween of .005". The outer end of the pin 25 is integrally connected, preferably, to the one end of a semi-circular arm 29 and the other end of this arm 29 is fixedly connected by any suitable means to the outer end of the body 20. It will be understood, that the vent 18 may be made to any desired size. The body 20 of the vent 18 is preferably made from cold rolled steel and the inner surface thereof is preferably highly polished to as fine a micro-finish as possible. The surface 27 of the pin 25 is also preferably highly polished to a fine micro-finish. The pin 25 may be formed from any suitable metal, as piano

wire, spring wire or drill rod. The arm 29 would be formed from the same material as the pin 25.

In operation, the air forcing the sand mixture into the corebox 10 will be vented to the atmosphere through the clearance around the pin 25. The arm 29 functions as a spring and may be called a spring arm whereby, when the air is vented through the body 20 the pin 25 vibrates in the body 20 and permits venting of the air but prevents the sand mixture from being blown out of the corebox

10. The vent 18 thus accomplishes a screening action or function without the serious defects of the prior art type vent screens. The vibrating pin 25 avoids any stoppage of air venting and will not become plugged up.

Figs. 7 and 8 merely show a prior art type screen vent used in shell molding which has a serious defect in that it plugs up easily and quickly. The numeral 30 indicates the cylindrical hollow body of the vent which is provided at the inner end thereof with a lip 31 and against the inner side thereof is seated a screen 32. A cross pin 33 is employed to retain the screen in place in the vent.

Fig. 5 illustrates how the vent of the present invention may be mounted in a corebox 10a which is adapted to make a shaped core. In such a case the vent 18a is mounted in the corebox 10a and the inner ends 21a and 26a of the body 20a and of the pin 25a, respectively, are ground off to the desired shaped end curvatures to match or mate with the shaped inner surface of the corebox 10a.

Fig. 6 illustrates the mounting of a vibratory pin 25b directly in a diverging hole 34 formed in the corebox wall of the corebox 10b. In this embodiment of the invention the spring arm 29b would be fixedly mounted by any suitable means directly in the corebox wall. The hole 34 would taper outwardly from the inner surface of the corebox to the outer surface thereof. The degree of tapers of the hole 34 and the pin 25b, and the clearance between the inner end of the pin 25b would be the same as given hereinbefore for the embodiment of Figs. 1 through 4.

If it is desired to enlarge the clearance between the inner end of the pins 25 this may be easily accomplished by merely springing the pins 25 inwardly and grinding off a portion to provide the desired increased clearance.

While it will be apparent that the preferred embodiments of the invention herein disclosed are well calculated to fulfill the objects above stated, it will be appreciated that the invention is susceptible to modification, variation and change without departing from the proper scope or fair meaning of the subjoined claims.

It will be seen, that the present invention includes the method of screen venting a corebox during the making of a shell core. The corebox would first be provided with an outwardly diverging hole through a wall of the corebox and this hole may be formed either directly in a wall of the corebox or in a separate body mounted in a wall of the corebox. A freely vibratory outwardly converging centrally located pin is then disposed in said diverging hole and is operatively held in said hole by means of a spring arm having one end thereof fixedly connected to the pin and the other end thereof fixedly connected to either the corebox or to the body.

What I claim is:

1. A method of screen venting a corebox during the making of a shell core comprising the steps of: first, providing an outwardly diverging hole through a wall of the corebox; and, second, mounting a freely vibratory outwardly converging centrally located pin in said diverging hole, whereby, air can be freely vented through said hole past said pin and the core sand will be retained in said corebox.
- 5 2. In combination, a shell molding corebox provided with an outwardly diverging hole through a wall thereof; an outwardly converging centrally located pin disposed in said inner end thereof even with the inner end of said hole and being concentrically spaced therefrom; and, means for retaining the pin in said hole in a freely vibratory condition.
- 10 3. The invention as set forth in claim 2, wherein: said outwardly diverging hole is formed in a wall of the corebox.
- 15 4. The invention as set forth in claim 2, wherein: said outwardly diverging hole is formed in a separate body mounted in a wall of the corebox.
- 20 5. In combination, a shell molding corebox provided with an outwardly diverging hole through a wall thereof; an outwardly converging centrally located pin disposed in said inner end thereof even with the inner end of said hole and being concentrically spaced therefrom; and, a spring arm having one end thereof fixedly connected to the corebox and the other end thereof fixedly connected to the pin for retaining the pin in said hole in a freely vibratory condition.
- 25 6. In combination, a shell molding corebox provided with an outwardly diverging hole through a wall thereof; an outwardly converging centrally located pin disposed in said inner end thereof even with the inner end of said hole and being concentrically spaced therefrom; said outwardly diverging hole being formed in a separate body mounted in a wall of the corebox; and, a spring arm having one end thereof fixedly mounted to the outer end of said body and the other end thereof fixedly mounted to the pin for retaining the pin in said hole in a freely vibratory condition.
- 30 7. A vent for a shell molding corebox comprising: a body having a hole therethrough with said hole diverging from one end of the body toward the other end of the body; a centrally located pin disposed in said hole in said body; said pin being truncated in shape with the larger end thereof being concentrically disposed in the smaller end of said diverging hole and being concentrically spaced therein; and, means for retaining the pin in said hole in a freely vibratory condition.
- 35 8. The invention as defined in claim 7, wherein: said means comprises a spring arm having one end thereof fixedly connected to the smaller end of said truncated pin and the other end thereof fixedly connected to the body.
